UNITED STATES PATENT OFFICE

170,836

INSTRUMENT FOR LOCATING HOLES FOR DOOR LOCKS

Adolf Schoepe, Fullerton, Calif., assignor to
Kwikset Locks, Inc., Anaheim, Calif., a corpo-
ration of California

Application January 26, 1953, Serial No. 23,283

Term of patent 14 years

(Cl. D54—13)

To all whom it may concern:

Be it known that I, Adolf Schoepe, a citizen of the United States, residing at Fullerton, in the county of Orange and State of California, have invented a new, original, and ornamental Design for an Instrument for Locating Holes for Door Locks, of which the following is a specification, reference being had to the accompanying drawings, forming part thereof, in which:

Fig. 1 is a top plan view of an instrument for locating holes for door locks, showing my new design;

Fig. 2 is a side elevational view thereof;

Fig. 3 is a bottom plan view thereof;

Fig. 4 is an elevational view taken in the direction of the arrow 4 of Fig. 1;

Fig. 5 is a rear end elevational view taken in the direction of the arrow 5 of Fig. 2;

Fig. 6 is a front end elevational view taken in the direction of the arrow 6 of Fig. 2; and

Fig. 7 is a fragmentary sectional view thereof taken on the broken line 7—7 of Fig. 6.

I claim:

The ornamental design for an instrument for locating holes for door locks, substantially as shown.

ADOLF SCHOEPE.
